UNITED STATES PATENT OFFICE.

FRANK DEVERE PATTEN, OF PORTLAND, OREGON.

AUTOMATIC GRAVITY-LOCK.

1,030,848.

Specification of Letters Patent. Patented June 25, 1912.

Application filed September 20, 1911. Serial No. 650,478.

To all whom it may concern:

Be it known that I, FRANK DEVERE PATTEN, a citizen of the United States, and resident of Portland, Multnomah county, 5 State of Oregon, have invented a new and useful Improvement in Automatic Gravity Locks, of which the following is a specification.

The object of my invention is to obtain a 10 lock, including a bolt, which is projected by a member operated by gravity instead of by a spring as in ordinary locks.

It is further my object to so arrange the parts that the key of the lock cannot be 15 withdrawn, when once inserted, until after the projection of the bolt, so that the act of removing the key may be made the basis of determining whether the lock has been locked or not.

20 My invention also embodies the specific features hereinafter fully set forth; and in connection with my improvement it is also my special purpose to so construct my lock that it can be inexpensively made without 25 sacrificing durability.

In the drawings my lock is shown as applied to the window sashes of a building, but, as apparent, it may be used with equal advantage on doors and all types of windows, including those of railway cars.

In the accompanying drawings: Figure 1 shows a partial interior elevation of a window frame, window sashes vertically movable therein and my improved lock in 35 place for locking, independently, the upper and lower sashes; Fig. 2 is a perspective detail showing a corner of the lower window sash, one stile of which is provided with a locking plate adapted to coöperate with the 40 bolt of my lock, which is mortised in the window frame, as also shown in this view; Fig. 3 is a sectional detail of the same parts shown in Fig. 1, also showing the lock, the front plate of which has been removed in 45 order to show the arrangement and operation of the locking mechanism; this view illustrating the position of the parts while the sash is being moved from one locking point to another; Fig. 4 is a side elevation 50 of my lock with the front plate removed, and shows the manner in which the bolt is projected by the gravity member; it also illustrates that the key, by which the gravity member is operated to retract the bolt, cannot 55 be withdrawn without the bolt first having been projected to its locking position; and

Fig. 5 shows a perspective view of the key suitable for operating my lock.

a represents a portion of the window frame, *b* the lower sash and *c* the upper sash. At *d* and *e* the window frame is provided with my locks by which the lower and upper window sashes are independently locked in place as desired. In order to adapt the window sashes to be locked in 60 place as mentioned, each thereof is provided, on the side face of the stile *b'*, with a longitudinal cavity *f*, in which is fastened a plate *g*, made with a plurality of ratchet teeth *g'*, and the stile face *b'* also having 65 bored therein holes *h* to receive the bolt *i* of the lock when projected. The lock comprises a case *j*, a reciprocable bolt *i*, provided with a slot at *i'* to receive the tongue *k*, of the gravity member *k'*, pivoted at *m*. 70 Normally the gravity member will operate to project the bolt *i* in the manner illustrated in Fig. 4. A stop pin *n* limits the downward movement of the long arm of the gravity member *k'*. The bolt *i* is formed 75 with a stud *o*, which is engaged by the bit *p* of the key *p'*. The key is placed on a pin, *q*, therefor provided in the case. The front plate of the lock is provided with the usual key hole *r*, but the slot thereof is 80 arranged at an oblique angle for the purpose of preventing the withdrawal of the key until it has been turned to the position which would project the bolt *i*, as illustrated in Fig. 4. The operation of turning 85 the key so as to lift the long arm of the gravity member *k'* and thus retract the bolt is 90 illustrated in Fig. 3.

In Figs. 3 and 4 *p* represents the key, and in Fig. 3 the dotted outline *p'* illustrates the fact that the key could not be withdrawn, that is to say, it could not be brought into the position required for withdrawing it from the slot of the case without first having moved the bolt *i'* into its locking position. In order to move a sash up or down, the key is first used to lift the long arm of the gravity member *k'*, so as to retract the bolt *i*; the sash is then arranged so as to bring one of the holes *h*, in the stile of the window sash, opposite the bolt *i*, which is thereupon automatically projected by the gravity member *k'*; and after having been so projected the key may be withdrawn. Should the bolt *i* of the lock 110 for any reason stick in the hole *h* of the stile, it would be forced into its projected

or locking position by the turning of the key in the lock in the act of withdrawing the former.

5 *s* represents the end-plate of the lock, and
t, a bearing for the stud end *o*, of the bolt *i*.
 The lock is mortised into the window case and is secured in place as usual. Parts not
 specifically described are understood to be
 a common arrangement and construction;
 10 and it is likewise to be understood that I
 do not confine myself in the construction
 of my lock to the particular details shown.
 In the lock case are provided pins *v* and *v'*,
 15 which the bit of the key is required to pass,
 and thus the lock can only be unlocked by
 the proper key.

The internally threaded studs *w*, *w'*, *w''*
 are for receiving screws for fastening the
 front plate of the lock.

20 I claim:

1. In a lock, the combination of a case,
 a bolt reciprocable in the case, adapted to
 be projected; a gravity member pivoted
 in the case having engagement with said
 25 bolt and adapted to normally project it;
 means in the case adapted for restraining
 the rotation of the key of the lock, when
 inserted, to a fixed axis; the parts being
 arranged to cause the long arm of the
 30 gravity member to be lifted by the bit of
 the key inserted in the lock by the turning
 of the key, whereby the bolt is retracted;
 and the case of the lock being adapted to
 prevent the withdrawal of the key from
 35 the lock until the bolt of the latter has been
 projected, so that the act of withdrawing
 the key assures that the bolt of the lock
 has been projected.

2. In a lock, the combination of a case,
 40 a bolt reciprocable in the case, adapted to
 be projected; a gravity member pivoted
 in the case having engagement with said
 bolt and adapted to normally project it;
 means in the case adapted for restraining
 45 the rotation of the key of the lock, when
 inserted, to a fixed axis; the parts being
 arranged to cause the long arm of the
 gravity member to be lifted by the bit of
 the key inserted in the lock by the turning
 50 of the key, whereby the bolt is retracted;
 and a projection on the bolt adapted for
 being engaged by the bit of the key when
 turned in the lock, said projection being
 adapted to prevent the complete turning of
 55 the key on its axis to the extent required
 to bring it to its withdrawing position un-
 less turned in the direction causing the pro-
 jection of the bolt, so that the act of with-
 drawing the key assures that the bolt of
 60 the lock has been projected.

3. In a lock, the combination of a case,
 a bolt reciprocable in the case, adapted to
 be projected; a gravity member pivoted in
 the case; said gravity member consisting
 65 of a long arm and a short pendent arm

terminating in a tongue, said tongue en-
 gaged with the bolt; means in the case
 adapted for restraining the rotation of the
 key of the lock, when inserted, to a fixed
 70 axis; the parts being arranged to cause
 the long arm of the gravity member to be
 lifted by the bit of the key inserted in the
 lock by the turning of the key, whereby the
 bolt is retracted; and the case of the lock
 75 being adapted to prevent the withdrawal
 of the key from the lock until the bolt of
 the latter has been projected.

4. In a lock, the combination of a case,
 a bolt reciprocable in the case, adapted to
 be projected, said bolt provided with a
 longitudinal slot; a gravity member pivoted
 in the case; said gravity member consisting
 80 of a long arm and a short pendent arm
 terminating in a tongue inserted in said
 slot of the bolt; means in the case adapted
 for restraining the rotation of the key of
 the lock, when inserted, to a fixed axis; the
 85 parts being arranged to cause the long arm
 of the gravity member to be lifted by the
 bit of the key inserted in the lock by the
 turning of the key, whereby the bolt is re-
 tracted; and a projection on the bolt adapt-
 90 ed for being engaged by the bit of the key
 when turned in the lock, said projection
 being adapted to prevent the complete turn-
 ing of the key on its axis to the extent re-
 quired to bring it to its withdrawing pos-
 95 ition unless turned in the direction causing
 the projection of the bolt, so that the act
 of withdrawing the key assures that the
 bolt of the lock has been projected.

5. In a lock, the combination of a case, a
 bolt reciprocable in the case, adapted to be
 projected; a gravity member pivoted in the
 case having engagement with said bolt and
 adapted to normally project it; means in
 105 the case adapted for restraining the rota-
 tion of the key of the lock, when inserted,
 to a fixed axis; the parts being arranged
 to cause the long arm of the gravity member
 to be lifted by the bit of the key inserted in
 110 the lock by the turning of the key, whereby
 the bolt is retracted; and a longitudinally
 projecting stud on the inner end of the bolt
 adapted for being engaged by the bit of the
 key when turned in the lock, said projecting
 115 stud being adapted to prevent the complete
 turning of the key on its axis to the extent
 required to bring it to its withdrawing pos-
 ition unless turned in the direction causing
 the projection of the bolt, so that the act of
 120 withdrawing the key assures that the bolt
 of the lock has been projected.

6. In a lock, the combination of a case, a
 bolt reciprocable in the case, adapted to be
 projected; a gravity member pivoted in the
 case; said gravity member consisting of a
 long arm and a short pendent arm termi-
 125 nating in a tongue, said tongue engaged
 with the bolt; means in the case adapted

- for restraining the rotation of the key of the lock, when inserted, to a fixed axis; the parts being arranged to cause the long arm of the gravity member to be lifted by the 5 bit of the key inserted in the lock by the turning of the key, whereby the bolt is retracted; and a longitudinally projecting stud on the inner end of the bolt adapted for being engaged by the bit of the key 10 when turned in the lock, said projecting stud being adapted to prevent the complete turning of the key on its axis to the extent required to bring it to its withdrawing position unless turned in the direction causing 15 the projection of the bolt, so that the act of withdrawing the key assures that the bolt of the lock has been projected.
7. In a lock, the combination of a case, a bolt reciprocable in the case, adapted to be projected, said bolt provided with a longitudinal slot; a gravity member pivoted in the case; said gravity member consisting of a long arm and a short pendent arm terminating in a tongue inserted in said slot of the bolt; means in the case adapted for restraining the rotation of the key of the lock, when inserted, to a fixed axis; the parts being arranged to cause the long arm of the gravity member to be lifted by the bit of the key 20 inserted in the lock by the turning of the key, whereby the bolt is retracted; a longitudinally projecting stud on the inner end of the bolt adapted for being engaged by the bit of the key when turned in the lock, said projecting stud being adapted to prevent the complete turning of the key on its axis to the extent required to bring it to its withdrawing position unless turned in the direction causing the projection of the bolt; and the case of the lock being provided with a key hole the slot of which is arranged to prevent the withdrawal of the key from the lock without first having been turned in the lock to such extent as to cause 25 the bit to project the bolt, so that the act of withdrawing the key assures that the bolt of the lock has been projected.
8. In a lock, the combination of a case, a bolt reciprocable in the case, adapted to be projected, said bolt provided with a longitudinal slot; a gravity member pivoted in the case; said gravity member consisting of a long arm and a short pendent arm terminating in a tongue inserted in said slot of the bolt; means in the case adapted for restraining the rotation of the key of the lock, when inserted, to a fixed axis; the parts being arranged to cause the long arm of the gravity member to be lifted by the bit of the key 30 inserted in the lock by the turning of the key, whereby the bolt is retracted; a longitudinally projecting stud on the inner end of the bolt adapted for being engaged by the bit of the key when turned in the lock, said projecting stud being adapted to prevent the complete turning of the key on its axis to the extent required to bring it to its withdrawing position unless turned in the direction causing the projection of the bolt; and the case of the lock being provided with a key hole the slot of which is arranged to prevent the withdrawal of the key from the lock without first having been turned in the lock to such extent as to cause 35 the bit to project the bolt, so that the act of withdrawing the key assures that the bolt of the lock has been projected.
